*Primary Examiner—Dominic Simone
Attorney, Agent, or Firm—Banner & Witcoff, LTD.***[57] CLAIM**

The ornamental design for a portion of a shoe upper, as shown and described.

DESCRIPTION

FIG. 1 is a perspective view of a portion of a shoe upper showing our new design;

FIG. 2 is a side elevational view thereof;

FIG. 3 is a top plan view thereof;

FIG. 4 is a front elevational view thereof; and,

FIG. 5 is a rear elevational view thereof.

The broken line showing of the eyelet and the remainder of the shoe is for illustrative purposes only and forms no part of the claimed design.
